UNITED STATES PATENT OFFICE.

ORVILLE U. DESHA, OF FORT COLLINS, COLORADO.

KEY ACTION FOR TYPEWRITING AND OTHER KEY-OPERATING MACHINES.

Application filed March 24, 1927. Serial No. 178,089.

My invention relates to improvement in key-action for typewriters and other type bar and key operating machines, actuating means at all times operatively connecting the type bar and key lever, moving the type bar to printing point upon the depression of the key lever and means reversely breaking the said connection after the printing impact of the type bar for the return of the type bar to normal position while the key lever is in depressed position, this broad object being the subject matter of an application filed by me on November 5th, 1923, Serial No. 672,871, upon which Patent 1,643,203 issued September 29, 1927, as a contradistinction between previous devices comprising a detachable connection or gap at some point between the key lever and type bar after the latter has been given the movement necessary to effect the printing and before the key lever has completed its movement.

The specific object of the present invention is to provide improved means of the character specified above whereby the reversely breaking actuating connection between the key lever and the type bar comprises two thrust links as a contradistinction between a reversely breaking actuating coupling comprising a thrust link and a draw link.

The desired principle of operation, new mechanical functions, operative expedients, and other objects and advantages will, hereinafter be described in the following disclosure and will be more particularly pointed out in the pending claims. In the accompanying drawings, like reference characters indicate corresponding parts in the various views.

In the drawings, Fig. I, is a vertical section of a typewriting machine, one key-action only being shown in normal position; Fig. II represents a view of the key mechanism similar to Fig. I, the key lever being shown in a depressed position and responding type bar. Fig. III also is a key mechanism similar to Fig. I, the key lever being shown in a depressed position and the type bar being returned to its initial position. Fig. IV is a skeleton view of the key mechanism for illustrative purposes in describing the mode of operation of the machine shown. It is understood, of course, that for clearness and to avoid complication of drawings the applicant has omitted to show or describe the remainder of key levers and type bars as well

as other devices necessary or advisable in the complete machine.

In the embodiment Fig. I, 1 indicates the frame of the typewriter, 1^a indicating the front and 1^b the rear, having a power driven paper carriage, the principal parts of the carriage not being shown in the drawings; 5 indicates a common platen carried by paper carriage; 6 indicates one of the usual type bars carrying type 7 at its front end, and arranged to turn on pivot 9 in the form of a segment disposed vertically above the frame 10, Fig. I, and providing the type 7 with a common printing point A, as the type bar 6 turns on pivot 9 from the normal horizontal position of rest on the segmental bed 11; 12 indicates one of the key levers carrying at the front end finger key 13, and pivoted at 14 intermediately of its end to bar 14^a Fig. I, and is kept normally in its elevated position by return spring 15 supported by depending arm 15^a of key lever 12 and bar 15^b at normal rest the key lever bearing against the under side of stop bar 15^c Fig. I, above the front part of the key lever 12.

The key lever 12 is described as having two incidents of operation; namely, the incident of depression and incident of release. The incident of depression is disclosed by the downward movement of key lever from radius B to radius C, and the incident of release is disclosed by the upward movement of key lever 12 back from radius C to radius B. The type bar 6 is described as having two incidents of operation; namely, the incident of response and the incident of release. The incident of response of type bar 6 is disclosed by the movement of the type bar from its initial rest radius E to printing point A, indicated by radius F forming arc G from pivot 9. The incident of recoil of type bar 6 is disclosed by its movement from its printing point A back to normal rest E. These incidents of operation are, of course, present in previous non-reversely breaking type bar action in so far as the incident of response E to A of the type bar 6 occurs simultaneously with the incident of depression B to C of key lever 12, and the incident of recoil, A to E, of the type bar occurs simultaneously with the incident of release C to B, of the key lever, but my invention relates to a latter correlation of incidents of operation of key levers with that of the type bar, in conforming to the reversely

breaking action by which the incident of response E to A of the type bar and incident of recoil A to E, occurs during the one incident of depression B to C, of the key lever.

5 18 indicates one of a series of vibratory levers disposed upwardly corresponding in number with type bar 6 and key lever 12. At their lower ends, the vibratory levers 18 are pivoted at 19 in a bar 20, Fig. I, extending 10 across the machine.

Means operatively connecting the type bar 6 and upper end of the vibratory lever 18 may be a flexible pull link 21 supported by pivots 21^a, 21^b, hereinafter further described.

15 Elements 22 and 23 establish a reversely breaking actuating coupling operatively connecting the key lever 12 and vibratory lever 18; 22 being a thrust link pivoted at 24 intermediately of its ends to the rear end of key 20 lever, and 23 being, also, a thrust link but hereinafter referred to as a trip link supported by pivot 25 intermediately the ends of the vibratory lever 18 and pivot 26, at all 25 times operatively connecting the thrust link 22 and vibratory lever 18, actuating the latter backwardly.

The thrust link 22 is provided with an angle stop 22^a at its lower end. Upon depression of the key lever 12, the thrust link 30 22 is moved bodily upward by the rear end of the key lever 12 and vibrates backwardly until the angle stop 22^a contacts with the under edge 12^a of the key lever 12 Fig. II. At this stage of operation, the backward vibration 35 of the thrust link 22 being limited, the element moves concurrently upward with the movement of the rear end of the key lever 12, hence the key lever 12 and thrust link 22 acts as a fulcrum to trip link 23 upwardly about the time the type 7 impacts the printing point A breaking reversely said coupling at pivot 40 26 while the key lever is in depressed position.

As the type bar 6 turns on the segmental pivot 9, pivot 21^a moves backward and downward causing the flexible link 21 to contact 45 with a segmental fulcrum return rod 27, the momentum of the type bar 6 from E to A causing the flexible link 21, Fig. II, to bow upward. The vertex of the curve, 21^c Fig. 50 II, of the flexible link 21 is completed about the time the elements 22 and 23 reversely break at pivot 26, and the energy thus stored in the flexible link 21 assists gravity in returning the type bar 6 and vibratory lever 18 to 55 normal position as shown in Fig. III while key lever 12 continues its downward incident of depression from D to C until it is stopped by the stop bar 28.

Means restoring said elements 22 and 23 to 60 normal operative position upon release of the key lever comprises a coil spring 29, one end thereof supported at 29^a by the depending arm 15^a of the key lever 12 and one end of said spring supported at 29^b by the forward 65 end of the thrust link 22. The normal opera-

tive position of elements 22 and 23 is determined by a cushion rod 30, the ends thereof secured at either side of the machine. Under the influence of spring 29, pivotal point 26 communicates with the forward part of cushion rod 30 limiting the backward movement of elements 22 and 23 until the key lever 12 is depressed. The normal position of the vibratory lever 18 is determined by its forward edge 18^a communicating with the rear part of the cushion rod 30—the cushion rod 30 effects smooth and quiet operation of the key mechanism.

The mechanical movements and operation thereof are important factors in providing the function for the improved key action. A further description of the operative principles therefore follows: The geometric circle H H Fig. IV, with a diametrical line J J, from the forward border pivot 24 to the backward border pivot 25 indicates the divert tension line dividing the actuating plane into a lower zone of response K and an upper zone of reaction L; the lower zone of response K having to do with the response of the type bar 6 from radius E to radius F as the key lever 12 is being depressed from radius B to radius D; and the upper zone of reaction L having to do with the recoil of the type bar from the printing point A to radius E at rest as the key lever 12 is being continually depressed from radius D to radius C of depression. Pivot 26 being the center of the actuating plane, the normal operative position of the thrust link 22 is in the forward radii of the actuating plane as shown in Figs. I, IV, and the normal operative position of trip link 23 is the backward radii of the actuating plane. By change in relative positions of the forward border pivot 24 and the backward border pivot 25, interior pivot 26 is brought upward within the upward zone of reaction L, the interior pivot 26 oscillating between the forward pivot 24 and backward border pivot 25 in crossing and recrossing the divert tension line J J. In this case, the elements 22 and 23 of the reversely breaking actuating coupling are subjected to unfoldment at the interior pivot 26 during the incident of depression from radius B to radius D of the key 110 lever 12 simultaneously with the incident of response of the type bar 6 from radius E to printing point A; and the elements 22 and 23 are subjected to foldment at the interior pivot 26 the remainder of depression, radius D to 115 radius C of key lever 12 simultaneously with the recoil of the type bar 6 from printing point A back to radius E.

The dotted line M M indicates the correlative relationship of the border pivots 24 and 125 25 and the interior pivot 26 during the process of operation, viz: Dotted line M M Fig. I, shows where the tri-pivotal relationship of pivots 24, 25 and 26 causes elements 22 and 23 of the reversely breaking actuating cou- 130

pling to form obtuse angle at the interior pivot 26 pointing upward within the lower zone of response during the normal position and effecting response of the type bar during the depression of the key lever 12. Dotted line M M Fig. II, shows about a 45-degree alignment of the border pivots 24 and 25 and interior pivot 26 of the reversely breaking actuating coupling forming straight angle of elements 22 and 23 at the time the type bar completes its response or impact and begins to recoil. Dotted line M M Fig. III, shows an obtuse angle of said elements 22 and 23 at the interior pivot 26 formed by the tri-pivotal relationship pointing upward within the zone of reaction L as the type bar 6 recoils while key lever is in depressed position.

It should be understood that the present improvement is capable of a large range of modification within the scope of the invention and that the improvement is not restricted to use in a machine of the type named, but may be employed wherever found available. Variations may be resorted to within the scope 25 of the invention, and portions of the improvement may be used without others.

What I claim as new and desire to secure by Letters Patent is:

1. In a typewriting machine, a type bar, a vibratory lever pivoted at its lower end, means operatively connecting the vibratory lever and type bar comprising a flexible pull link, a key lever pivoted intermediately of its ends, actuating means at all times operatively connecting the key lever and vibratory lever to move the type bar to the printing point upon the depression of the key lever, means actuating said connection to return the type bar after the printing impact while the key lever is in depressed position, means restoring said connection to normal operative position upon release of the key lever.

2. In a typewriting machine, a type bar, a vibratory lever in the rear of the machine pivoted at its lower end, means operatively connecting the vibratory lever and type bar comprising a flexible pull link, a key lever pivoted intermediately of its ends, actuating means at all times operatively connecting the vibratory lever and key lever comprising a reversely breaking actuating coupling for moving the type bar to printing point upon depression of the key lever, means reversely breaking said coupling after the printing impact to return the type bar to normal position while the key lever is in depressed position, means restoring said coupling to normal operative position upon release of the key lever.

3. In a type key action, a type bar, a vibratory lever pivoted at its lower end, means operatively connecting the vibratory lever and type bar comprising a flexible pull link, a key lever pivoted intermediately of its ends, actuating means operatively connecting the

key lever and vibratory lever comprising a reversely breaking actuating coupling having the elements thereof unfolded, the elements of said coupling moving the type bar to printing point upon depression of the key lever, means folding said elements reversely breaking said coupling after the printing impact of the type bar, means restoring the folded elements of said coupling to normally unfolded upon the release of the key lever.

4. In a typewriting machine, a type bar, a vibratory lever pivoted at its lower end, means operatively connecting the vibratory lever and type bar comprising a flexible pull link, a key lever pivoted intermediately of its ends, a reversely breaking actuating coupling operatively connecting the vibratory lever and key lever comprising two thrust links moving the type bar to printing point upon depression of the key lever, means reversely breaking said coupling after printing impact of the type bar for returning the type bar to normal position while key lever is in depressed position, means restoring said coupling to normal operative position upon release of the key lever.

5. In a typewriting machine, a type bar, a vibratory lever pivoted at its lower end disposed vertically and its upper end thereof vibrating backwardly, means operatively connecting the vibratory lever and type bar comprising a flexible pull link, a key lever pivoted intermediately of its ends, a reversely breaking actuating coupling operatively connecting the vibratory lever and key lever moving the type bar to the printing point upon depression of the key lever, means reversely breaking said coupling after printing impact of the type bar for returning the type bar to normal position while the key lever is in depressed position, means restoring said coupling to normal operative position upon release of the key lever.

6. In a type key action, a type bar, a vibratory lever pivoted at its lower end, means operatively connecting the vibratory lever and type bar comprising a flexible pull link, a key lever pivoted intermediately of its ends, a reversely breaking actuating coupling operatively connecting the key lever and vibratory lever comprising a trip link, and a thrust link pivoted intermediately of its ends to the rear end of the key lever for moving the type bar to the printing point upon depression of the key lever, means reversely breaking said coupling after printing impact of the type bar, means returning the type bar to normal position while key lever is in depressed position, means restoring said coupling to normal operative position upon release of the key lever.

7. In a typewriting machine, a type bar, a vibratory lever pivoted at its lower end, a key lever pivoted intermediately of its ends, means operatively connecting the vibratory lever and type bar comprising a flexible pull

- link, actuating means at all times operatively connecting the vibratory lever and key lever comprising a thrust link, and a trip link connecting the thrust link and vibratory lever
- 5 actuating the latter by backward thrust for moving the type bar to printing point upon depression of the key lever, means reversely breaking said coupling after printing impact of the type bar for returning the type bar to
- 10 normal position while the key lever is in depressed position, means restoring said coupling to normal operative position upon release of the key lever.
8. In a type key mechanism, a type bar, a vibratory lever pivoted at its lower end, means operatively connecting the vibratory lever and type bar comprising a flexile pull link, a key lever pivoted intermediately of its ends, a reversely breaking actuating coupling
- 15 operatively connecting the key lever and vibratory lever comprising a trip link and a thrust link, a border pivot connecting the rear end of the trip link and vibratory lever, a forward border pivot connecting the key
- 20 lever and thrust link, an interior pivot below a line drawn through the border pivots connecting the thrust link and trip link for moving the type bar to printing point upon depression of the key lever, means actuating
- 25 the interior pivot upward across a divert tension line between the forward border pivot and the backward border pivot reversely breaking said coupling after printing impact of the type bar for returning the type bar to
- 30 the interior pivot upward across a divert tension line between the forward border pivot and the backward border pivot reversely breaking said coupling after printing impact of the type bar for returning the type bar to
- 35 normal position while the key lever is in depressed position, means restoring said coupling to normal operative position upon release of the key lever.
9. In a type key action, a type bar, a vibratory lever pivoted at its lower end, means operatively connecting the vibratory lever and type bar comprising a flexile pull link, a key lever pivoted intermediately of its ends, a reversely breaking actuating coupling operatively connecting the key lever and vibratory lever comprising a thrust link and a trip link, a backward border pivot connecting the thrust link and vibratory lever, a forward border pivot connecting the key lever and trip
- 40 link, an interior pivot below a reversely breaking line drawn through the border pivots operatively connecting the thrust link and trip link for moving the type bar to printing point upon depression of the key lever, means actuating said thrust link and trip link moving the interior pivot above said reversely breaking line drawn through said border pivots for reversely breaking said mechanism after printing impact of the
- 45 type bar for returning the type bar to normal position while the key lever is in depressed position, means actuating said trip link and thrust link restoring said interior pivot to normal operative position below said reversely breaking line drawn through said

border pivots upon release of the key lever.

10. In a typewriting machine, a type bar, a vibratory lever pivoted at its lower end, means operatively connecting the vibratory lever and type bar comprising a flexile pull link, a key lever pivoted intermediately of its ends, a reversely breaking actuating coupling operatively connecting the key lever and vibratory lever comprising a trip link and a thrust link moving the type bar to printing point upon depression of the key lever, an angle stop at the lower edge of the thrust link communicating with the lower edge of the key lever reversely breaking said coupling after printing impact of the type bar for returning the latter to normal position while the key lever is in depressed position, means restoring said coupling to normal operative position upon the release of the key lever.

breaking said connection after the printing impact of the type bar for returning the type bar to normal position while key lever is in depressed position, a coil-spring supported by said depending arm of the key lever and thrust link restoring said coupling to normal operative position upon release of the key lever.

14. In a key action for a key-operating machine, a type bar, a vibratory lever, means operatively connecting the vibratory lever and type bar, a key lever, a reversely breaking actuating coupling operatively connecting the key lever and vibratory lever moving the type bar to printing point upon depression of key lever, means reversely breaking

said coupling after the printing impact of the type bar for returning the latter to normal position while key lever is in depressed position, a cushion rod in front of said vibratory lever and beneath said reversely breaking actuating coupling communicating with the forward edge of the vibratory lever and communicating with the lower edge of said coupling to effect smooth and quiet operation of said elements and determine their normal position after operation. 20 25

Signed at Fort Collins, in the county of Larimer and State of Colorado, this 19th day of March, A. D. 1927.

ORVILLE U. DESHA.
